SELF-PUNCHING AND RETAINING PAPER HOLDER

Arthur M. Ste. Marie, Old Town, Maine, assignor
to T. M. Chapman's Sons Co., Old Town, Maine,
a corporation of Maine

Application November 14, 1947, Serial No. 785,964

4 Claims. (Cl. 24—252)

1

This invention relates to a holder for holding and displaying sheets of paper containing advertising matter, posters and the like, and it has for its object to provide a novel construction by which the sheet of paper to be displayed can be easily impaled on supporting pins or prongs and then clamped in position.

In order to give an understanding of the invention, I have illustrated in the drawings a selected embodiment thereof which will now be described and after which the novel features will be pointed out in the appended claims.

In the drawings:

Fig. 1 is a front view of a device embodying my invention illustrating the manner in which a sheet of paper is supported thereby.

Fig. 2 is an enlarged rear view of the device.

Fig. 3 is a fragmentary view of the clamping member.

Fig. 4 is an enlarged section on the line 4—4, Fig. 2.

Fig. 5 is an enlarged section on the line 5—5, Fig. 2.

Fig. 6 is an enlarged end view of the device showing the clamping member in open position.

Fig. 7 is an enlarged fragmentary sectional view showing the manner in which the spring arms act against the clamping member.

The device herein shown comprises a supporting member 1 which is preferably made of sheet metal and is provided adjacent its lower edge with a plurality of forwardly extending prongs 2 on which the sheet of paper 5 may be impaled. The supporting member 1 may be attached to a wall in any approved way, and for this purpose it is shown as provided at its upper edge with a plurality of apertures 3 adapted to receive screws by which the said member may be screwed to the wall or to receive the ends of a chain or cord by which said supporting member is hung on the wall.

Adjacent the lower edge of the supporting member 1 is a clamping member 4 which functions both to impale the upper edge of the sheet 5 on the prongs 2 and to clamp said sheet against the supporting member 1.

This clamping member 4 is shown as made of sheet metal. It is channel shape in cross section and presents the spaced parallel top and bottom leg portions 6 and 7 and the front or bridge

portion 8 by which the top and bottom portions are connected. The clamping member is also provided with an upstanding clamping flange 9 which rises from the rear edge of the bottom leg portion 7. The clamping flange 9 is provided with openings 10 which register with the prongs 2 and through which the prongs extend when the clamping member is in its operative clamping position.

10 The clamping member 4 is hingedly connected to the supporting member 1 so that it can be swung from its open position shown in Fig. 6 into its closed operative position shown in Figs. 4 and 5.

15 When the clamping member is in its open position, the clamping flange 9 is withdrawn from the prongs 2 thereby leaving a space between the ends of the prongs and the clamping flange through which the upper edge of the sheet 5 to be displayed may be inserted as shown in Fig. 6. After the sheet has been thus positioned, swinging movement of the clamping member from its open to its closed position will cause the clamping flange 9 to bear against the sheet 5 and will force the prongs 2 through the sheet thereby impaling the sheet on the prongs.

20 When the clamping member is in its closed position, it clamps the upper edge portion of the sheet 5 against the supporting member 1 and thus holds the sheet properly supported by the prongs 2.

25 Spring means are provided which tend normally to hold the clamping member yieldingly in its closed position, but which permit the member to be swung into the open position shown in Fig. 6. The top leg portion 6 of the clamping member is provided with two rearward extensions 11 which extend through openings or slots 12 with which the member 4 is provided, and the portion of each extension 11 which projects beyond the rear face of the supporting member 1 is curved slightly as shown at 13 to provide a recess 14 on its under face.

30 The spring means for yieldingly holding the clamping member in its closed position is herein illustrated in the form of two lengths of spring wire 15, each of which is secured at one end to the supporting member 1, and the other end 16 of which is received in the recess 14 of one of the 40 extensions 11.

The supporting member 1 is provided with two rearwardly displaced portions 17 which provide holding means for retaining the spring wires 15 in position, said wires lying against the rear face of the supporting member 1 and extending underneath the displaced portions 17. The inner end of each spring wire 15 is shown as bent laterally as indicated at 18, such laterally bent portion lying against the rear face of the supporting member and serving to hold the spring wire in its proper position. As stated above, the free end 16 of each spring wire engages an extension 11 of the clamping member in the rear of the supporting member, and since the spring arms are normally under tension, each arm exerts an upward pressure against the corresponding extension 11.

When the clamping member 4 is moved into its opened position shown in Fig. 4, the extensions 11 swing downwardly thereby increasing the tension of the spring arms 15, and when the clamping member is released, the resiliency of the arms or wires 15 exerts an upward pressure on the extensions 11 which tends to swing the clamping member into its closed position.

The supporting member may be provided with a peripheral rearwardly directed flange 19 which serves to space the body of the supporting member 1 sufficiently from the wall to which it is attached to allow free play of the extensions 11 as the clamping member is opened and closed.

The clamping member is preferably provided centrally with a thumb piece extension 20 which may be grasped when said member is to be swung into its open position.

The clamping member is also provided with a sight opening 21 through which a slip of paper may be displayed containing any desired information. This sight opening is provided for by a channel shaped member 22 which embraces the front face of the clamping member and which has the sight opening 21 formed therein. Said member 22 is retained in position by means of screws 23. When the screws are removed, the member 22 may be also removed and by placing the slip of paper within the member 22, and then replacing it on the clamping member, the desired reading matter will be visible through the sight opening 21.

The device herein shown is simple in construction and inexpensive to manufacture, and it is well adapted to hold sheets of paper carrying any kind of material which is to be displayed. Such sheets of paper may be in the form of advertisements or in the form of posters, or may carry rules and regulations for factory operations, or any other desired reading matter. Merely for illustrative purposes the word "Notice" appears on sheet 5 in Fig. 1 to indicate the reading matter carried by said sheet.

To mount a sheet of paper in the holder, it is only necessary for the operator to grasp the thumb piece 20 and raise the clamping member into the open position shown in Fig. 6 and then insert the upper edge of the sheet between the clamping member and the supporting member as also shown in Fig. 6, and then to return the clamping member to its closed position. During the return movement, the clamping flange 9 will impale the upper edge of the sheet on the prongs 2, and the clamping member when in operative position will hold the sheet thus impaled.

I claim:

1. A device of the class described comprising a supporting plate having adjacent its lower edge

a plurality of forwardly projecting paper-piercing and supporting prongs and also having a plurality of openings above the prongs, a clamping member of sheet metal channel shape in cross section and presenting spaced top and bottom leg portions connected by a front portion and directed rearwardly from said front portion, said bottom leg portion having an upwardly extending clamping flange rising from its rear edge, which flange has openings to receive the prongs, the top portion of the clamping element having rearward extensions extending through the openings in the supporting plate and forming hinge members for the clamping member, and spring means on the rear of the supporting plate acting against said extensions and serving to yieldingly hold the clamping member in operative position.

2. A device of the class described comprising a supporting plate having adjacent its lower edge a plurality of forwardly projecting paper-piercing and supporting prongs and also having a plurality of openings above the prongs, a clamping member of sheet metal channel shape in cross section and presenting spaced top and bottom leg portions parallel to each other and connected by a front portion, the top and bottom leg portions being directed rearwardly towards the supporting plate, said bottom leg portion having an upwardly extending clamping flange rising from its rear edge and provided with openings to receive the prongs, the top portion of the clamping member having rearward extensions extending through the openings in the supporting plate and forming hinge members for the clamping member, and resilient arms anchored to the supporting plate on the rear thereof and having their free ends engaging the extensions, said arms acting through the extensions to yieldingly hold the clamping member in operative position.

3. A self punching and retaining paper holder comprising a supporting plate having adjacent its lower edge a plurality of forwardly projecting paper-piercing and supporting prongs, a clamping member of sheet metal channel shape in cross section and presenting top and bottom leg portions connected by a bridge portion, the open side of said clamping member being directed toward the supporting plate, means associated with the rear edge of the top leg portion for hingedly connecting said clamping member to the supporting plate, the bottom leg portion of said clamping member having at its rear edge an upstanding clamping flange provided with openings to receive the prongs, spring means located entirely on the back side of the supporting plate and acting on the hinge connection between the clamping member and the supporting plate for yieldingly holding the clamping member in operative clamping position, said upstanding clamping flange resting flatly against the supporting plate when the clamping member is in clamping position.

4. A device of the class described comprising a supporting plate having adjacent its lower edge a plurality of forwardly projecting paper-piercing and supporting prongs and also having a plurality of openings above the prongs, a clamping member channel shape in cross section and presenting parallel spaced top and bottom leg portions and a connecting front or bridge portion, the top and bottom leg portions being directed rearwardly towards the supporting plate, the top leg portion having rearward extensions extending through the openings in the supporting plate, the terminal portions of said extensions

on the rear of said plate each being curved to present a groove on its under face extending parallel to the supporting plate, spring wires, one for each rearward extension, anchored to the supporting plate on the rear thereof, each spring wire having its end portion engaging in the groove of one of the rearward extensions, said spring wires acting through said rearward extensions to yieldingly hold the clamping member in clamping position, the rear edge of the bottom leg of the clamping member having an upstanding clamping flange which lies flatly against the supporting plate when the clamping member is in clamping position, said flange having openings to receive the prongs.
